UNITED STATES PATENT OFFICE.

ADELAIDE HEALD, OF WASHINGTON, DISTRICT OF COLUMBIA.

DESIGN FOR A COMBINED GARTER AND POWDER-PUFF RECEPTACLE.

58,316.

Specification for Design.

Patented July 12, 1921.

Application filed February 21, 1917. Serial No. 150,285. Term of patent 7 years.

To all whom it may concern:

Be it known that I, ADELAIDE HEALD, a citizen of the United States, residing at No. 1719 Oregon avenue, in the city of Washington, District of Columbia, have invented a new, original, and ornamental Design for Combined Garter and Powder-Puff Receptacles, of which the following is a specification, reference being had to the accompanying drawing, forming part thereof, the same being a perspective view of a combined garter and powder-puff receptacle comprising my new design.

Reference being had to the drawing it will be seen to illustrate a continuous band, preferably of elastic material, and shirred throughout its circumference for purposes of ornamentation. At one side this band is provided with a pocket having a closure-

flap and fastening means as shown, intended primarily for the reception of a powder-puff. As thus shown and described, the device is designed, arranged and adapted to encircle the leg of a user where it may perform the functions of an ordinary garter, and in addition those for which it is primarily intended.

My new and ornamental design having been thus shown and described, I claim:

The ornamental design for a combined garter and powder-puff receptacle as shown and described.

In testimony whereof I affix my signature in the presence of two subscribing witnesses.

ADELAIDE HEALD.

Witnesses:

Wm. E. DYRE,
M. D. BALLAUF.
